CLAIM

The ornamental design for an article of jewelry, as shown and described.

DESCRIPTION

FIG. 1 is a perspective view of an article of jewelry showing my new design;

FIG. 2 is a front view thereof;

FIG. 3 is a right side elevational view thereof;

FIG. 4 is a rear view thereof;

FIG. 5 is a left side elevational view thereof;

FIG. 6 is a top plan view rotated 180 degrees thereof;

FIG. 7 is a bottom plan view thereof; and,

FIG. 8 is a perspective view of a second embodiment of FIG. 1.

The broken lines in FIGS. 1 and 8 are for purposes of illustration only and form no part of the claimed design.
